UNITED STATES PATENT OFFICE.

CHARLES E. CAMERON, OF PHILADELPHIA, PENNSYLVANIA, ASSIGNOR TO U. S. HAME COMPANY, OF BUFFALO, NEW YORK, A CORPORATION OF NEW YORK.

HAME.

1,123,093.

Specification of Letters Patent. Patented Dec. 29, 1914.

Application filed December 23, 1910. Serial No. 599,005.

To all whom it may concern:

Be it known that I, CHARLES E. CAMERON, citizen of the United States, residing at Philadelphia, in the county of Philadelphia and State of Pennsylvania, have invented certain new and useful Improvements in Hames, of which the following is a specification.

The object of the invention is to construct a hame of metal, thereby increasing the strength and durability of the hame and at the same time lessening the cost of manufacture.

Reference will be had to the accompanying drawing forming a part of this specification and wherein like numerals of reference designate corresponding parts throughout the several views, in which:

Figure 1 is a side elevation of one of the hame members partly broken away in section, Fig. 2 is an enlarged side elevation of the upper end thereof, parts being broken away in section, Fig. 3 is a side elevation of a fragment of the upper portion of the hame, with parts broken away in section, Fig. 4 is a transverse sectional view taken on the line 4—4 of Fig. 1, Fig. 5 is a similar view taken through line 5—5 of Fig. 2, and, Fig. 6 is a plan view of a lower fragment of the hame.

Reference numeral 1 designates one of the members of a pair of hames, formed of a single piece of sheet metal, preferably iron or steel. The upper end of the hame member is bent outwardly and gradually tapers, and is substantially circular in cross section; the lower end of the hame member tapers but slightly and is bent inwardly. The portion of the hame member intermediate the said upper and lower bent portions, is substantially triangular in cross section, as illustrated in Fig. 4, the three walls forming said triangle being irregular; the outer wall 4 being substantially flat; the wall 5 being slightly concave to fit the collar; and the wall 6 being slightly bent to form an obtuse angle.

Secured to the flat outer wall 4 by means of rivets 7, is a reinforcing strip 8, preferably of sheet brass. The upper end 9 of this strip terminates adjacent the bend of the upper end portion 2 of the hame member and gradually decreases in width and is slightly concaved to conform to and fit the adjacent rounded tapering portion of

the hame member. This end of the strip 8 also gradually decreases in thickness, terminating in a very thin end 9'. The lower end of the strip 8 extends beyond the lower end of the body of the hame member and is curled inwardly to form a hinge-barrel 10 for the strap loop 11, which latter may be of any suitable type and hingedly connected to the said hinge-barrel 10 by means of a rivet or bolt 12. The said rivets 7 which secure the reinforcing strip 8 in position on the hame member, extend entirely through the latter and are upset, as indicated by numeral 7', at the junction of the walls 5 and 6 of the hame member.

Arranged on the reinforcing strip 8 are the usual fastenings and guides. The trace fastening 14 is of staple form, the two legs 15 thereof being abruptly decreased in diameter to form shoulders 16 which seat 75 against the strip 8, the legs 15 extending through said strip and the body of the hame member and being upset against the wall of the latter, thereby firmly securing the fastening in position. Located above 80 the trace fastening adjacent the upper portion of the hame member, is a ring-terret 17 provided with opposite flat wall-positions 18 (see Fig. 4) firmly engaged by the eye 19 formed on the end of a rivet 20, which latter passes through and is riveted in the body of the hame member. An elongated slot or aperture 21 in the strip 8 receives the eye portion 19 of the rivet, preventing undue movement thereof. Above the terret, is an 90 inverted U-shaped top-strap connection 22, the two legs 23, 23' of which extend into recesses formed in the reinforcing bar, said legs being shouldered so as to also bear upon said reinforcing strip. Extending from the 95 intermediate portion of the body or bridge of the top-strap connection, is a stem 27 which passes through and is riveted in the hame member. The portion of said stem adjacent the bridge 22, is enlarged as at 28, 100 said portion serving as a dividing medium for the strands of the top-strap.

The upper end portion of the hame member is inclosed in a tubular brass horn 29, bent and tapered to conform to the curvature and taper of the hame end. The lower end of the horn is provided with a notch 30 which receives the upper leg 23' of the fastening 22, thereby preventing rotary movement of said horn. A tapered wooden plug 110

31 having a central longitudinal bore 32 is
forcibly inserted into the tapered upper end
of the hame member, the upper ends of the
plug, hame member, and horn being flush
5 and abutting the inner wall of an ornamental
cap 33, which is slipped over the
end of the horn and secured by means of a
nail or pin 34 driven into the bore of the
said wooden plug. The head 35 of the nail
10 is finished off so as not to be conspicuous.
For further ornamentation, brass headed
rivets 36 are inserted, with their heads on
the exposed side 6 of the hame member.

Having described the invention, what is
15 claimed as new and useful and desired to
be secured by Letters Patent is:

1. In a device of the character described,
a tubular metal body formed of a single
20 piece of material, a metal reinforcing strip
secured thereto; a tubular horn inclosing
the upper end of the body and strip, a
wooden plug in the upper end of the body,
a cap engaging the horn, and a pin inserted
25 in the said plug and cap and securing said
horn to the body.

2. In a device of the character described,
a tubular metal body formed of a single
30 piece of material, a metal reinforcing strip
secured thereto, the upper ends of the body
and strip being tapered, a tapering wooden
plug in the upper end of the body, a cap
engaging the horn, and a pin inserted in
35 said plug and cap and securing said horn
to the body.

3. In a device of the character described,
a tubular metal body formed of a single
piece of material, a tapering wooden plug
frictionally secured in the upper end of the
40 body, a tubular horn inclosing the upper
end of the body and terminating flush

therewith, a cap inclosing the upper end of
the horn and engaging the same and the
upper end of the body, and a pin inserted
5 into the wooden plug and securing the cap
in place.

4. In a device of the character described,
a tubular metal body formed of a single
piece of sheet metal, a metal reinforcing
strip secured thereto and provided with re-
cesses closed at their bottoms by said body, 50
a substantially U-shaped top connection
having a central stem passing entirely
through said strip and body, the leg por-
tions of said U-shaped top connection being
seated in said recesses, the strip and body 55
having tapering upper ends, and a tapering
tubular horn inclosing the upper ends of
the body and strip, said horn being pro-
vided with a notch co-incident with one of
the recesses and receiving one of the leg 60
portions of the top connection.

5. A metal hame comprising a single
piece of sheet metal bent into a hollow shell
having its longitudinal edges brought to-
gether along the outer face of the hame, 65
and a cover strip secured upon the outer
face of said hame and concealing said edges.

6. A metal hame comprising a single
piece of sheet metal bent into a hollow
shell having its longitudinal edges abutting 70
along the outer face of the hame, and a
cover strip secured to the outer face of said
hame which conceals the joint between said
abutting edges.

In testimony whereof I affix my signature
75 in presence of two witnesses.

CHARLES E. CAMERON.
